GAS TREATING APPARATUS

Hart E. Delvin, Gary, Ind.

Refiled for application Serial No. 581,717, December 17, 1931. This application July 23, 1934, Serial No. 736,605.

6 Claims. (Cl. 261—91)

My invention relates to gas treating apparatus, and it consists in the combinations, constructions, and arrangements herein described and claimed.

5 An object of my invention is to provide apparatus whereby the exhaust gases of an internal combustion engine may be rendered comparatively harmless.

10 A further object of my invention is to provide a method of treating the products of combustion of an internal combustion engine in such a manner as to greatly reduce, if not entirely prevent, the poisonous action of these gases upon breathing organisms.

15 A further object is to provide means adaptable to be connected to the exhaust pipe of an automotive vehicle which will act as a combination muffler and liquid-spraying device.

20 A further object of my invention is to provide means whereby the heated gases of combustion of an internal combustion engine may be subjected to a bath of liquid in a manner whereby these gases may be rendered less poisonous to human beings.

25 A further object of my invention is to provide means whereby the objectionable odor of the gases of combustion may be reduced, if not entirely obviated.

30 A further object is to provide means whereby the solid particles of the gases of combustion may be trapped.

35 A further object is the provision of means whereby the objectionable characteristics of the heated gases of combustion may be modified so as to render these gases substantially innocuous.

A further object is to provide means whereby these gases may be subjected to a scrubbing after they have been forced through a suitable liquid.

40 Other objects and advantages will appear in the following specification, and the novel features of the invention will be particularly pointed out in the appended claims.

45 My invention is illustrated in the accompanying drawings, forming part of this application, in which

Figure 1 is a top plan view showing the device of my invention operatively connected to the exhaust pipe of an automotive vehicle and being provided with an electrical circuit for indicating the amount of oil in the apparatus.

50 Figure 2 is an elevational view of the apparatus.

55 Figure 3 is a section taken along the line 3—3 of Fig. 2, and

Figure 4 is an enlarged sectional view taken along the line 4—4 of Figure 2.

In carrying out my invention, I make use of apparatus indicated generally by the numeral 1 having a lower section 2, an upper section 3, and an intermediate section 4. The apparatus may be also provided with a motor 5. The motor 5 may be operatively connected to a central shaft 6 for purposes hereinafter described.

The lower section 2 consists in part of a circular base portion 7, a cylindrical outer wall portion 8, and a tubular oil indicating means 9. The cylindrical wall portion 8, the base portion 7, and the oil indicating means 9 may be welded or otherwise connected together in any suitable manner, such as, for instance, is indicated in Figure 1.

The indicating means 9 may be tubular in form and have an upright portion 10 provided with a cap 11. The upright portion 10 is provided with an elongated opening 12 provided with a curved glass window 13 which is fitted in the opening in a water-tight manner. The window 13 may be calibrated, as shown, for the purpose of indicating the height of the oil in an inner container 15. The inner container 15 is formed by the inner portion of the base 7 and a hollow cylindrical wall member 16 having an annular heat insulating air space 16'. The wall member 16 may be provided with a plurality of apertures 17 and an upper inclined outwardly extending flange 18.

The cylindrical outer wall portion 8 and the cylindrical wall member 16 as well as a portion of the base 7 is provided with an annular insulating lining 19. The lining 19 may be made of any suitable insulating material adapted to withstand the action of the heated parts of combustion as they pass around the annular chamber 20 after having entered the apparatus through the tubular connection 21 and the opening 22.

The tubular connection 21 may be welded or otherwise secured to the cylindrical outer wall portion 8 and may be provided with a threaded collar means 23 whereby connection may be made with a pipe 24, see Figure 2, a portion of which may be curved so as to provide a coil 25. The pipe 24 may be connected to the end of an exhaust pipe or muffler 26 any any suitable manner, such as by a tapered tubular member 27.

If desired, the hollow interior of the pipe 24 may be provided with a flexible helical means 28. The reduced end portion 27 and the flexible means 28 each tend to reduce the velocity of the exhaust gases as they pass through the pipe 24 into the apparatus 1.

A baffle member 29 may be fixedly secured opposite the opening 22 in any manner whereby the gases entering the annular chamber 20 may be directed downwardly and around the container 15. If desired, the baffle member 29 may extend downwardly to within a short distance of the base 7.

The container 15 may be provided with an inverted conical member 30, the lower and central portion of which is cut out to form an opening 31. The conical member 30 provides means whereby the liquid contents of the container 15 may be prevented from overflowing when the car is tilted or subjected to unusual vibration. A metal supporting strip 33 may be connected to the conical member 30 substantially as shown and secured thereto by any other suitable means. This strip 33 is provided with a centrally disposed opening 34 for the purpose of admitting a pipe 35 in which is fitted the rod 6 having a spiral flange 38.

The rod 6 is adapted to rotate within the pipe 35 in such a manner as to raise upwardly any fluid which may be in the container 15. The lower end 39 of the pipe 35 may be open and provided, if desired, with any suitable screening means, not shown, whereby foreign matter may be prevented from entering the tubular means 35. The pipe 35 may also be provided with a fixed collar 40 for the dual purpose of supporting the tubular means and preventing the tubular means from touching the base 7. The collar 40 may be secured to the strip 33. The strip 33 may also be provided with openings 41 for the purpose of receiving rods 42 to the lower end of which is secured a floating means 43.

The floating means 43 may be provided with a central opening 44 in a manner permitting the float to move upwardly or downwardly with respect to the pipe 35.

One of the rods 42 may be provided with a rigidly connected collar 45 having a pivoted extension 46 to which is secured a crank means 47. The crank means 47 is operatively connected to a switch means 48. The switch means 48 may be provided with a contacting lever, not shown, which is operatively connected to the crank means 47 and a plurality of contact means operatively connected to suitable resistance units. This switch means 48 may be operatively connected by any suitable conductors such as 32 and 49, to a meter 50, and any suitable source of electric current not shown. The switch means 48 is well known to the art and requires no detailed description. The purpose of the float 43, the switch means, and the meter 50 is to indicate the position of the oil in the inner container 15. The switch means may be rigidly connected to the strip 33 in the manner indicated in Figure 1.

The intermediate section 4 may consist of an outer tubular wall 51 provided with an internal shoulder 52. The shoulder 52 is provided for the purpose of supporting an annular fluid trough means 53.

A metal cone 54 may be either rigidly or slidably secured at the central and top portion to the upper end of the pipe 35. This cone may be made of copper. The lower end of this cone is so positioned within the annular fluid trough member 53 that when the member 53 is filled with the fluid, all gases passing from the lower section 2 into the upper section 3 must pass through the liquid. A conical perforated screen member 56 may also be secured to the upper portion of the tubular member 35 just above the metal cone 54.

The circumferential edge 57 of this screen may be clampingly secured in position by a circular wire gasket 58 and the flanges 60 and 59 of the outer tubular wall 51 and the casing 61. The casing 61 forms the wall and top portion of the upper section 3.

The tubular rod 35 at its upper end is provided with a tongue or extension 62 which may be operatively connected to the shaft 63 of the motor 5 substantially as shown in Figure 1. Above the screen member 56, I have provided a collar member 64 which may be rigidly secured to the rod 35 in any suitable manner. The collar 64 is provided with a plurality of openings 67 adapted to receive wire brush means 68, the upper portion of which may be clampingly secured in the openings 67 by screws 69. The brush means 68 may be formed of a plurality of twisted wires which clampingly secure brushes 72 which may be made of metal wire. These brushes distribute the liquid and cool the liquid which has been raised from the container 15 and serve to remove any oil film from the cone 56.

The casing 61 may be enlarged at the upper end as is indicated at 73 and provided with a plurality of circumferentially disposed openings 74 through which the products of combustion may pass out of the apparatus into the atmosphere. The upper section 3 is provided with a perforated cylindrical member 75 and an inwardly extending circular member 76. The circular member 76 is provided with a large central opening 77 through which the rod 35 passes. The circular member 76 and the perforated cylindrical member 75 may be secured to the casing 61 in any suitable manner.

The perforated member 75 may also be provided with a perforated annular flange member 78 which is rigidly secured to the casing 61 and the perforated cylindrical member 75 in any suitable manner, such as by welding. Within the chamber 40 formed by the perforated cylindrical member 75, the perforated flange 78 and the casing 61, is inserted an annular screen 79. This annular screen 79 may be made of any suitable material, such as, for instance, a perforated or "stabbed" metal plate which has been wound in a plurality of layers to provide a means whereby any liquid still remaining in the exhaust products of combustion may be retained within the apparatus.

The liquids caught by the screen member 79 descend through the perforated members 78 and 75 and pass through perforations 80 in the vertical circular member 76 into the annular trough member 53. Positioned above the collar 64 and the member 76 is a propeller or fan 81 which is rigidly secured to the rod 35 by means of the screw 82.

A cylindrical baffle 70 may encircle the propeller in a manner which is best understood by referring to Figure 1. The baffle may be fixedly secured to an upper portion 83 of the casing 61. The central portion of the upper portion 83 may be provided with an integral collar 84. The motor 5 may be operatively secured to the shaft 35 in any suitable manner, such as, for instance, by means of a bracket member 85. The bracket member may be rigidly secured to the upper portion 83 by bolts 86. Integral bosses 87 of the top portion 83 having threaded recesses 88 may be provided for the purpose of receiving the bolts 86.

The motor 5 may be provided with a sleeve 89 in which is fixedly secured the motor shaft 63. The rod 37 and the shaft 63 may be provided with

grooves 90 and 90' whereby liquid may be carried upwardly in the shaft by capillary attraction.

Suitable bearing means, such as indicated at 91, may be provided in order that the motor armature may be suitably supported in a rotatable manner. If desired, the upper end of the motor shaft 63 may be provided with a slotted screw or other suitable means 92, whereby the motor shaft may be turned by a screwdriver or the like 10 should the shaft become "frozen" to the motor frame. The screw 92 also provides means for retaining a cover washer 93 and a bearing 94. The upper portion of the motor may be provided with a downwardly inclined drain means 95, 15 whereby any oil carried to the top of the shaft may be caught and prevented from injuring the insulation of the motor wiring.

The container 15 may be filled by passing the fluid through the tubular oil indicating means 9. 20 I have, however, provided a threaded opening 100 in the intermediate section 4 and a threaded plug member 101 for closing this opening. I have also employed a tubular drain member 102 for the purpose of enabling the liquid to pass over 25 the annular chamber 20 and into the inner container 15. The annular chamber 20 may, if desired, be provided with an opening 103 and a plug 104.

From the foregoing description of the various 30 parts of the device, the operation thereof may be readily understood. When the device has been properly assembled and connected to the exhaust conduit 26, the container 15 may be filled with any suitable fluid and the motor 5 energized. The 35 liquid is drawn upwardly through the tube 35 by the rotation of the flanged tubular rod 37. This liquid is discharged outwardly at the upper end of the tube 35 and the great portion of the liquid is discharged upon the conical member 54. 40 The liquid is then drained into the trough means 53 and the device is now ready to receive the incoming products of combustion. These products of combustion enter the device through the opening 22 and are deflected downwardly by the baffle member 29. The incoming products of combustion are thereby given a rapid circular motion and most of the solid products of combustion are thrown against the outer portion of the insulating lining 19 and fall to the lower portion of the 45 chamber 20. The rotating gases continue their circular motion and pass out at the upper end of the chamber 20 and enter the space between the conical member 30 and the cone 54. In doing this they pass under an annular flange 32 from 50 which the liquid overflowing from the trough member drops to the conical member 30.

In passing this descending stream of liquid, the gases of course become impregnated with the liquid. These gases also force a certain amount 60 of the liquid toward the interior. The inner chamber in which the gases now find themselves is therefore heavily saturated with heated liquid vapor. The heat is intense, and certain chemical changes occur here, the nature of which is not 65 thoroughly understood.

While I have discovered that water and many other liquids may be used advantageously, I have found that the use of a mineral oil is extremely 70 efficient, particularly the more refined oils. A mineral oil of the type often used internally has proved itself particularly efficient. While in this chamber, the liquid and the gases are cooked and a certain portion of the cooked products fall downwardly and are removed from circula-

tion. The gases are now forced upwardly against the cone 54 where they are deflected into the annular trough 53. The liquid in the trough 53 of course further wets and weights the products of combustion and deposits them in the trough, from which they are expelled by reason of the liquid in the trough overflowing at certain times. The cooked and liquid scrubbed products of combustion now arise from the liquid in the trough 53 and ascend upwardly through the perforated 10 cone 56 and come in contact with the rapidly rotating brush means 68.

The brush means 68 serve a double purpose. They tend to clean the perforations in the cone 56 and at the same time impart to the wetted products of combustion a rotating motion which forces the wetted products against the wall 61 and the circular member 76. Upon striking these surfaces, the greater portion of the moisture in the products of combustion is removed.

These gaseous products are now thrown upwardly through the opening 77 and are there again given a rapid circular motion by the propellers 81. The propellers 81 throw the products of combustion directly against the baffle 70 upon 25 which the wetted products of combustion again lose more of their moisture. After passing under the baffle 70, the gases pass through the member 75 and come in contact with the screen 79. One form of the screen 79 consists of a perforated 30 or "stabbed" plate having a cut-away directly depending portion 110. These cut-away portions tend to gather a certain proportion of the remaining moisture of the products of combustion. This moisture passes downwardly through the 35 flanged member 78 and the circular member 76. After passing the screen 79, the exhaust gases now pass out of the apparatus. Repeated and exhaustive experiments have proven that the treated gases are no longer as dangerous to life 40 as they were before being treated.

The heat insulating air space 16' surrounded by the hollow cylindrical wall 16 provides means whereby the fluid in the container may be prevented from being unduly heated by the heat 45 of the combustion products. This air space, while not indispensable to the operation of my device, enables the liquid in the container to be used for a longer time than would otherwise be possible.

This application is a refile for my forfeited 50 application No. 581,717, filed Dec. 17, 1931, and allowed Dec. 15, 1932.

I claim:

1. A device of the character described adapted for operative connection to an exhaust conduit of 55 an internal combustion engine and including a casing provided with a gas inlet port, a gas outlet port, a gas passageway communicating with said ports, a liquid container forming part of said passageway, inclined baffle means for guiding the 60 gas into the liquid container, said device being also provided with a liquid reservoir, means for passing the liquid from the liquid reservoir to the baffle means, said baffle means being adapted to drain the liquid into the liquid container, and 65 means for returning liquid from said container to said reservoir.

2. A device of the type described adaptable for operative connection to an exhaust conduit of an internal combustion engine and including a casing, an oil reservoir disposed in the casing, a gas inlet port, a gas outlet port, a gas passageway in part surrounding said reservoir and communicating with said ports, a liquid container disposed above the reservoir and forming part of the pas- 75

- sageway, rotatable means for passing the liquid from the reservoir into the upper portion of the casing, and conical means for guiding the liquid into the liquid container.
5. A device of the type described adaptable for operative connection to an exhaust conduit of an internal combustion engine and including a casing, an oil reservoir disposed in the casing, a gas inlet port, a gas outlet port, a gas passage-way in part surrounding said reservoir and communicating with said ports, a liquid container disposed above the reservoir and forming part of the passageway, rotatable means for passing the liquid from the reservoir into the upper portion of the casing, and conical means for guiding the liquid into the liquid container, the conical means having an outer portion projecting into the container, said outer portion serving as a baffle means for deflecting the products of combustion into the liquid reservoir.
10. 3. A device of the type described adaptable for operative connection to an exhaust conduit of an internal combustion engine and including a casing, an oil reservoir disposed in the casing, a gas inlet port, a gas outlet port, a gas passageway in part surrounding said reservoir and communicating with said ports, a liquid container disposed above the reservoir and forming part of the passageway, rotatable means for passing the liquid from the reservoir into the upper portion of the casing, and conical means for guiding the liquid into the liquid container, the conical means having an outer portion projecting into the container, said outer portion serving as a baffle means for deflecting the products of combustion into the liquid reservoir.
15. 4. A device of the type described adaptable for operative connection to an exhaust conduit of an internal combustion engine and including a casing, an oil reservoir disposed in the casing, a gas inlet port, a gas outlet port, a gas passageway in part surrounding said reservoir and communicating with said ports, a liquid container disposed above the reservoir and forming part of the passageway, rotatable means for passing the liquid from the reservoir into the upper portion of the casing, and conical means for guiding the liquid into the liquid container, the conical means having an outer portion projecting into the container, said outer portion serving as a baffle means for deflecting the products of combustion into the liquid reservoir.
20. 5. Apparatus of the class described comprising a casing, a liquid reservoir therein, an open top liquid container in said casing above the liquid level of said reservoir, an inclined baffle having its lower edge positioned within said container beneath the liquid level thereof, liquid elevating means in said casing for raising liquid from said reservoir to the upper side of said baffle whereby the liquid is discharged into said container, means for operating said elevating means to cause the liquid to fill said container and overflow into said reservoir, an inlet port for directing gas into said container below said baffle, and an outlet port for said gas on the opposite side of said baffle.
25. 6. Apparatus of the class described comprising a casing, a liquid reservoir therein, an open top liquid container above said reservoir, an inclined baffle above said container having its lower edge positioned within said container beneath the liquid level thereof, liquid elevating means in said casing comprising a rotary member for raising liquid from said reservoir to said container, means for operating said elevating means to cause the liquid to fill said container and overflow into said reservoir, a gas inlet port for conducting gas into said casing beneath said baffle, an outlet port for the gas on the opposite side of said baffle, and rotary means secured to said shaft between said baffle and outlet port for removing liquid from the gas.

HART E. DELVIN. 35
